UNITED STATES PATENT OFFICE.

SOLOMON RITTER HIPPLE, OF WILLIAMSPORT, PENNSYLVANIA, ASSIGNOR TO D. X. INSTRUMENT COMPANY, OF HARRISBURG, PENNSYLVANIA, A CORPORATION OF DELAWARE.

RHEOSTAT.

Application filed September 6, 1922. Serial No. 586,433.

To all whom it may concern:

Be it known that I, SOLOMON RITTER HIPPLE, a citizen of the United States, residing at the city of Williamsport, county of 5 Lycoming, State of Pennsylvania, have invented certain new and useful Improvements in Rheostats; and I do hereby declare the following to be a full, clear, and exact description of the invention, such as will enable others skilled in the art to which it 10 appertains to make and use the same.

The invention relates to a new and useful construction of rheostat adapted to produce extremely fine or delicate adjustments or 15 regulations of electrical current, the instrument being particularly applicable to radio installations, but in no sense limited to such application. To this end, the invention comprises an insulating casing containing a 20 body of granular conducting material, terminals located at opposite ends of said casing, with the granular material between them, one of said terminals being adjustable within the casing and having associated 25 therewith a piston working within the casing and operating on the granular material to apply varying degrees of compressive force thereto, to increase or decrease the 30 resistance to an electric current traversing the granular material, said adjustable terminal preferably having a pointed end, beyond the piston, which still further regulates the extent of contact of the terminal with the 35 granular material and admits of the finest contact adjustments between the terminal and the granular material. These and other 40 objects of the invention will be set forth in detail in the annexed specification, predicated on the accompanying drawings, in which:—

Fig. 1 is a perspective plan view of the rheostat;

Fig. 2 is a plan view partly in section.

Referring to the drawings, 1 indicates a 45 base, preferably formed of metal or other conductive material, having openings 2 at opposite ends thereof to permit the rheostat to be attached to a suitable support, such, for example, as the panel of a radio set. 50 Projecting from the base 1 is a casing 3 of suitable insulating material, such, for example, as cartridge paper or the like, which will permit the inner end of the casing to be crimped inwardly, as at 4. Mounted 55 within the casing 3 is a tubular sleeve 5,

preferably made of glass or other suitable insulating material, to provide a smooth cylindrical bore, within which sleeve there is confined a body of loose granular conducting material, such as comminuted carbon, 60 or a mixture of carbon and a suitable granulated metal.

Mounted in a screw-threaded opening in the base 1 is a screw-threaded spindle 7, which is adjustable longitudinally of the 65 axis of the casing 3 and the tubular sleeve 5, said spindle preferably being provided with a tapered inner end, which contacts with the granular material 6, and having on its outer end a handle or knob 8 which is secured to 70 the spindle by a suitable set screw 9. Secured to the spindle 7 near the inner end thereof is a piston 10, which may conveniently be attached to the spindle by means of a fixed washer 11, which may be of metal 75 soldered or brazed to the spindle, a movable washer 12 and a set-nut 13, the latter serving to clamp the piston firmly in position and expand the same so that its peripheral surface will be in close engagement with the 80 interior of the tubular sleeve 5.

Mounted in the inner end of the housing, comprising the casing 3 and the sleeve 5, is a fixed terminal comprising a spindle 15 85 preferably provided with a conical inner end projecting within the granular material, and a fixed collar 16, said spindle having a screw-threaded outer portion. Mounted on said spindle is a washer 17, preferably of metal, an insulating washer 18 fitting snugly 90 within the tubular member 5, a washer 19 fitting within the casing 3 and resting against the end of the tubular member 5, a washer 20 adapted to overlie and engage the inturned or crimped end portion 4 of the 95 casing 3, and nuts 21 and 22 which serve to confine the various washers on the spindle 15 and to clamp the crimped edge 4 of the casing 3 firmly between the washers 19 and 20.

As thus constructed, the rheostat is adapted to be mounted on the panel of the apparatus to which it is applied, by means of the base 2, so that the spindle 7 projects forwardly of the panel. The circuit in 105 which the rheostat is interpolated is connected to the fixed terminal, preferably between the nuts 21 and 22, and to the movable terminal by connecting one end of the circuit wire under one of the screws which 110

secure the base 1 to the panel or support. As thus applied, the rheostat is generally horizontal, so that when the spindle 7, which constitutes the movable terminal, is 5 screwed outwardly, the piston 10 will recede from the granular material 6, and when the pressure on the latter is released, the portion thereof adjacent the piston 10 and the tapered end of the spindle will flow 10 forward in the tubular member 5 until the surface of the material attains the normal angle of repose. If the pointed end of the spindle 7 is then wholly out of contact with the granular material, no current will flow. 15 By turning up the screw spindle 7, by means of the handle 8, until the tip of the pointed end of the spindle just engages the surface of the granular material, the minimum current will be permitted to pass, and the 20 amount of current may be increased gradually and by very small increments as the spindle 7 is turned up, and the pointed end thereof driven deeper into the body of granular material. The continued forward 25 movement of the spindle 7 will cause the piston 10 to force the granular material in the tubular member 5 into a gradually compacted mass, the resistance to the flow of the current between the terminals and 30 through the granular material being inversely proportional to the degree of compression between the particles of the granular material as imposed by the piston. It will be apparent, therefore, that the current flowing through the rheostat may be varied 35 by practically infinitesimal amounts between the limits of maximum and no current, by proper adjustments of the movable terminal, and as the screw-threads on the 40 spindle 7 are preferably very fine, it will be apparent that extremely delicate regulation of the current, to meet the most exacting conditions, may be effected, first, by the extent of engagement or contact between the 45 relatively long tapered end of the adjustable terminal and the granular material, and second, by the extent or degree of compression imposed on the granular material 50 confined between the two terminals.

50 In order to maintain the body of granular conducting material 6 in properly loosened condition, there is preferably mounted within the sleeve 5, and between the piston 10 and the washer 18, a helical spring 23 55 which is retained normally under compression. Any movement of the spring due to the adjustment of the terminal 7 will serve to agitate the granular material and move the particles thereof relatively to each other, 60 and prevent the particles being permanently compacted. When the terminal 7 and piston 8 are retracted, the spring 23 expands longitudinally and the various convolutions thereof stir up and loosen the granular ma-

terial. When the terminal 7 and the piston 10 are advanced, the spring 23 is compressed and the movement of the convolutions thereof also agitates and displaces the elements of the granular material. The spring 23 is preferably made of non-conductive material, or, if made of metal, is completely coated with an insulating medium to prevent contact between the metal thereof and any of the conductive elements of the rheostat. 75

What I claim is:

1. A rheostat comprising an insulating casing, a body of granular conductive material therein, terminals in said casing adapted to engage said granular material, one of said terminals being adjustable within the casing and having a piston thereon for compressing the granular material and a tapered end engaging said material. 80

2. A rheostat comprising an insulating casing, a body of granular conductive material therein, a fixed terminal at one end of the casing, and an adjustable terminal at the other end having a piston thereon for compressing the granular material and a 90 tapered end engaging said material.

3. A rheostat comprising a base, a tubular shell connected to the base having an inwardly crimped outer end; a sleeve of insulating material within the shell; a terminal in one end of the shell including a threaded spindle, a washer on the spindle engaging the top of the sleeve, a second washer on the spindle engaging the crimped end of the sleeve, and a nut on the spindle to clamp the crimp between the washers; a terminal mounted in said base and projecting within said sleeve, said terminal including a threaded spindle engaging a threaded opening in the base, and a piston fixed to said spindle and slidable in said sleeve; and a body of granular material in said sleeve between said terminals. 95 100 105

4. A rheostat comprising a base, a tubular shell connected to the base having an inwardly crimped outer end; a sleeve of insulating material within the shell; a terminal in one end of the shell including a threaded spindle, a washer on the spindle engaging the top of the sleeve, a second washer on the spindle engaging the crimped end of the sleeve, and a nut on the spindle to clamp the crimp between the washers; a terminal mounted in said base and projecting within said sleeve, said terminal including a taper-ended threaded spindle engaging a threaded opening in the base, and a piston fixed to said spindle and slidable in said sleeve; and a body of granular material in said sleeve 110 115 120 125 between said terminals.

In testimony whereof I affix my signature.

SOLOMON RITTER HIPPLE.
